CONVERSION OF HYDROCARBON OILS

Charles H. Angell, Chicago, Ill., assignor to Universal Oil Products Company, Chicago, Ill., a corporation of Delaware

Application December 11, 1935, Serial No. 53,876

12 Claims. (Cl. 196—49)

This invention particularly refers to an improved process for the conversion of hydrocarbon oils employing two cooperative cracking stages wherein relatively high-boiling oils, comprising 5 intermediate liquid conversion products of the process and any high-boiling fractions of the charging stock, are subjected to relatively mild cracking conditions in the first stage while relatively low-boiling oils, comprising low-boiling 10 conversion products from the first stage and any desired low-boiling fractions of the charging stock, are subjected to more severe cracking or reforming conditions in the second stage, and with provision for recovering liquid residue from 15 either or both cracking stages or for reducing residual liquid from either or both cracking stages to substantially dry coke in a cooperative coking stage of the system.

One specific embodiment of the invention comprises subjecting an oil of relatively high-boiling 20 characteristics, recovered from within the system, as will be later described, to conversion conditions of cracking temperature and superatmospheric pressure in a heating coil, introducing 25 the heated products into an enlarged chamber wherein separation of vaporous and liquid conversion products is accomplished, withdrawing the latter from said chamber, subjecting the vaporous conversion products to fractionation in 30 commingled state with hydrocarbon oil charging stock for the process, whereby the commingled oils are separated into selected relatively low-boiling and high-boiling fractions, returning the selected high-boiling fractions from said fractionating step to the heating coil for conversion, 35 recovering any selected desirable low-boiling fractions from the fractionating step, subjecting other selected relatively low-boiling fractions from the fractionating step to independently 40 controlled conversion conditions of cracking temperature and superatmospheric pressure in a separate heating coil, cooling the heated products from said separate heating coil sufficiently to prevent any substantial further conversion thereof, 45 separating the resulting products into vapors and non-vaporous residue, removing the latter from the zone of separation, subjecting the vapors to fractionation whereby their insufficiently converted components are condensed as reflux 50 condensate, returning the reflux condensate to the first mentioned heating coil for further conversion, subjecting fractionated vapors of the desired end-boiling point from the last mentioned fractionating step to condensation and recovering 55 the resulting distillate.

Residual liquid recovered from either the relatively light oil cracking operation or the relatively heavy oil cracking operation, or both, may be removed from the system as a final residual product thereof or a portion or all of either or both of these materials may be heated to a relatively high temperature under non-coking conditions in a separate heating coil and thence introduced into an enlarged coking chamber wherein their high-boiling components are reduced to 10 substantially dry coke, vaporous products from the coking operation being returned either to the same chamber to which the hot conversion products from the first mentioned heating coil are supplied or to the separating zone to which the 15 partially cooled products from said separate heating coil are supplied or, in part, to both these zones.

The features and advantages of the present process will be readily apparent to those familiar 20 to the cracking art, particularly with reference to the accompanying diagrammatic drawing and the following description thereof. The drawing illustrates one specific form of apparatus embodying the features of the invention and several of the various modifications of the embodiment of the invention above outlined, which are contemplated within the scope of the invention, 25 are indicated in the drawing and described in conjunction therewith.

Referring to the drawing, charging stock for the process, which may comprise any desired type of oil ranging from straight-run gasoline, naphtha or other light distillate through the various fractions of crude petroleum to fuel or 35 heavy residual oil and specifically including crude petroleum or other oil of relatively wide boiling range which may contain straight-run or cracked motor fuel or motor fuel fractions, is supplied through line 4 and valve 2 to pump 3 40 by means of which it may be fed through line 4 and valve 5 into fractionator 6 to commingle therein with the hot vaporous conversion products supplied to this zone, as will be later described, whereby the charging stock is subjected 45 to substantial vaporization and to fractionation together with the vaporous conversion products, or, when desired, the charging stock may be diverted from line 4 and passed, all or in part, through line 4', valve 5' and line 94 into chamber 7 wherein it commingles with the hot conversion products supplied to this zone, as will be later described, and is therein subjected to substantial vaporization, its vaporized components passing therefrom, as will be later more 55

fully described, to fractionation in fractionator 6.

High-boiling components of the vaporous conversion products condensed as reflux condensate in fractionator 6 commingle with any non-vaporous components of the charging stock supplied to this zone and the commingled materials are withdrawn from the lower portion of the fractionator through line 8 and valve 9 to pump 10 by means of which this material is fed through line 11, valve 12 and line 13 to conversion in heating coil 14.

A furnace 15 of suitable form supplies the required heat to the oil passing through heating coil 14 to subject the same to the desired conversion temperature, preferably at a substantial superatmospheric pressure, and the resulting hot conversion products are discharged through line 16 and valve 17 into chamber 7.

Chamber 7, which may function as a reaction zone or as a reduced pressure vaporizing chamber, may be operated at any desired pressure ranging from substantially atmospheric to substantially the same pressure as that employed at the outlet from heating coil 14. Separation of the vaporous and non-vaporous components of the conversion products supplied to chamber 7 is accomplished in this zone and when charging stock is supplied thereto its low-boiling components are vaporized and commingle with the vaporous conversion products while any high-boiling components of the charging stock, similar in boiling range to the residual liquid conversion products separated from the vapors in this zone, commingle with said residual liquid. The residual liquid products are withdrawn from the lower portion of chamber 7 through line 18 and may be directed, all or in part, through line 19 and valve 20 to cooling and storage or elsewhere, as desired or they may be directed, all or in part, as will be later more fully described, to further treatment within the system. The vaporous conversion products are withdrawn from the upper portion of chamber 7, together with vaporous components of any charging stock supplied to this zone, and directed through line 21 and valve 22 to fractionation in fractionator 6.

The vaporous conversion products thus supplied to fractionator 6 are separated in this zone, together with any charging stock supplied thereto, into selected relatively low-boiling and high-boiling fractions. The high-boiling fractions are withdrawn, as previously described, from the lower portion of the fractionator and supplied to heating coil 14.

Selected low-boiling fractions are withdrawn together with uncondensable gas from the upper portion of the fractionator and directed through line 23 and valve 24 to condensation and cooling in condenser 25. The resulting distillate and gas passes through line 26 and valve 27 to collection and separation in receiver 28. Uncondensable gases may be released from the receiver through line 29 and valve 30. A portion or all of the distillate may, when desired, be directed from receiver 28 through line 31 and valve 32 to storage or elsewhere, as desired.

In case the total motor fuel conversion products of this stage of the system and any gasoline or gasoline fractions contained in the charging stock are of satisfactory antiknock value preferably only this material is withdrawn in vaporous state from the upper portion of the fractionator, condensed and recovered, as described, in receiver 28, or, in case only selected low-boiling components of the motor fuel conversion prod-

ucts and any corresponding fractions of the charging stock are of satisfactory antiknock value, the distillate collected in receiver 28 is preferably limited to such material. On the other hand in case the low-boiling components of the commingled charging stock and vaporous conversion products do not contain any appreciable quantity of materials within the boiling range of motor fuel which are of good antiknock value, the total motor fuel components of the commingled materials, either alone or together with selected somewhat higher boiling fractions thereof such as, for example, naphtha, kerosene or kerosene distillate, light gas oil and the like, are recovered, as described, in receiver 28, in which case all or a regulated portion of this material is directed from receiver 28 through line 33 and valve 34 to pump 35 by means of which it is supplied to further conversion or reforming in heating coil 41, as will be later more fully described.

In case motor fuel or motor fuel fractions of satisfactory antiknock value are recovered in receiver 28 somewhat higher boiling components of the commingled vaporous conversion products and charging stock, including any motor fuel fractions of inferior antiknock value and also preferably including somewhat higher boiling oils such as naphtha, kerosene, kerosene distillate, light gas oil and the like, are withdrawn as condensate from one or a plurality of suitable intermediate points in the fractionator, provision being made in the case here illustrated for supplying such material from the fractionator through line 36 and valve 37 to pump 35, by means of which it is directed to heating coil 41 for further conversion.

The relatively low-boiling oil supplied, as described, to pump 35 is directed therefrom through line 38 and may pass therefrom, all or in part, through line 39 and valve 40 to heating coil 41. Preferably, however, a regulated portion or all of this material is directed through valve 42 in line 38 to heat exchanger 43, wherein it passes in indirect heat exchange with the stream of hot conversion products discharged from heating coil 41, serving to partially cool said conversion products and being thereby preheated, the preheated oil passing from heat exchanger 43 through line 44 and valve 45 to heating coil 41.

Heating coil 41 is located within a furnace 46 of suitable form by means of which the relatively low-boiling oil supplied to this zone is heated to the desired relatively high conversion temperature under any desired pressure conditions ranging from substantially atmospheric to 1000 pounds, or more, per square inch superatmospheric pressure. A substantial superatmospheric pressure of several hundred pounds per square inch is, however, preferred in heating coil 46 particularly in case any substantial quantity of materials of poor antiknock value within the boiling range of motor fuel are supplied to this zone for reforming. The stream of highly heated products is discharged from heating coil 41 through line 47 and valve 48 and is preferably directed through heat exchanger 43 wherein substantial cooling of the hot conversion products is accomplished, as previously described, the partially cooled products being directed from heat exchanger 43 through line 49, valve 50 and line 51 into separating chamber 53.

It is, of course, entirely within the scope of the invention to by-pass heat exchanger 43 and/or to employ other means for cooling the

stream of hot conversion products from heating coil 41. Such other cooling means may comprise, for example, the introduction of a suitable cooling oil into the stream of hot conversion products from heating coil 41, by well known means not illustrated. Such cooling oil may comprise, for example, selected final or intermediate liquid products of the process such as distillate from receiver 69, a portion of the total or selected fractions of the reflux condensate from fractionator 54 and the like.

Chamber 53, in the case here illustrated, comprises the lower portion of column 52, the upper portion of which comprises fractionator 54, although separate structures may, of course, be employed for these two zones, when desired. In case heating coil 46 is operated at a substantial superatmospheric pressure a substantially reduced pressure is preferably employed in chamber 53, pressure reduction being accomplished either by the regulation of valve 48 in line 47 or valve 50 in line 49, or both. This reduction in pressure serves to additionally cool the conversion products supplied to chamber 53 and also serves to assist vaporization in this zone. Separation of the vaporous and residual liquid components of the materials supplied to chamber 53 is accomplished therein, the latter being withdrawn from the lower portion thereof through line 55 wherefrom they may, when desired, be directed, all or in part, through line 56 and valve 57 to cooling and storage or elsewhere, as desired, or this material may be directed, all or in part, to further treatment for its eventual reduction to coke, as will be later more fully described. Vaporous products pass from chamber 53, through a suitable partition 58 into fractionator 54, wherein their components boiling above the range of the desired final light distillate product of this stage of the process are condensed as reflux condensate.

The reflux condensate formed in fractionator 54 is withdrawn from the lower portion thereof, above partition 53, through line 59 and valve 60 to pump 61 by means of which it is supplied through line 62, valve 63 and line 13 to conversion in heating coil 14, in the manner previously described.

Fractionated vapors of the desired end-boiling point are withdrawn, together with uncondensable gas, from the upper portion of fractionator 54 and directed through line 64 and valve 65 to condensation and cooling in condenser 66. The resulting distillate and uncondensed gas passes through line 67 and valve 68 to collection and separation in receiver 69. Uncondensed gases may be released from the receiver through line 70 and valve 71. Distillate may be withdrawn from receiver 69 through line 72 and valve 73 to storage or to any desired further treatment. When desired, regulated quantities of the distillate collected in receiver 69 may be recirculated by well known means, not illustrated in the drawing, into the upper portion of fractionator 54 to serve as a refluxing and cooling medium in this zone for assisting fractionation of the vapors and to maintain the desired vapor outlet temperature therefrom. This same expedient may also be employed, when desired, for cooling and assisting fractionation of the vapors in fractionator 6 by returning regulated quantities of the distillate from receiver 28 to fractionator 6 by well known means, not illustrated.

It is, of course, also within the scope of the invention, when desired, to separate the reflux

condensate formed in fractionator 54 into selected relatively low-boiling and high-boiling fractions, in which case only the relatively high-boiling fractions are supplied from the lower portion of the fractionator to conversion in heating coil 14, in the manner previously described, while selected lower boiling fractions are withdrawn by well known means, not illustrated, from one or a plurality of suitable intermediate points in the fractionator and may, when desired, be returned by well known means, not illustrated, to further conversion in heating coil 41. This method of operation is particularly advantageous in case the vaporous products undergoing fractionation in column 52 contained high-boiling motor fuel fractions which are of unsatisfactory antiknock value and which may, by the method described, be returned to further treatment in heating coil 41. It may also be desirable in case the oil supplied to heating coil 41 from receiver 28 or fractionator 6 contains materials above the boiling range of motor fuel, in which case materials of similar boiling range may be supplied, in the manner described, from fractionator 54 to heating coil 41.

A portion or all of the residual liquid withdrawn from chamber 7 through line 18, as previously described, may, when desired, be directed through valve 74 in this line to pump 75 by means of which it is directed through line 76, 30 valve 77 and line 78 to further treatment in heating coil 79. The invention also contemplates further treatment, when desired, of a regulated portion or all of the residual liquid from chamber 53 in heating coil 79, in which case this material may be directed through valve 80 in line 55 to pump 81 by means of which it is supplied through line 82, valve 83 and line 78 to heating coil 79.

Heating coil 79 is located within a suitable furnace 84 by means of which the oil supplied to the heating coil is preferably heated to a relatively high conversion temperature without allowing it to remain in this zone for a sufficient length of time to permit any substantial formation and deposition of coke in the heating coil and communicating lines. The stream of highly heated relatively high-boiling oil is discharged from heating coil 79 through line 85 and valve 86 into coking chamber 87 wherein its high-boiling components are reduced to substantially dry coke by means of heat supplied to the oil passing through heating coil 79.

Chamber 87 may be operated at any desired pressure ranging from substantially atmospheric to a superatmospheric pressure of several hundred pounds per square inch which, however, is no greater than that employed at the outlet from heating coil 79. The coke produced in chamber 87 may be allowed to accumulate within this zone to be removed therefrom in any well known manner, not illustrated, after the chamber has been substantially filled or after its operation has been discontinued for any other reason and preferably after it has been isolated from the rest of the system. Chamber 87 is provided with a drain line 89 controlled by valve 90 which may also serve, when desired, as a means of introducing steam, water or other suitable cooling material into the chamber after its operation is completed and after it has been isolated from the rest of the system in order to hasten cooling and facilitate removal of the coke. A plurality of coking chambers may, of course, be employed, when desired, although only one is illustrated.

in the drawing, in which case the chambers preferably are alternately operated, cleaned and prepared for further operation in order that the coking stage, in common with the rest of the system, may be operated continuously. Vaporous products are withdrawn from the coking chamber through line 91 and may be directed through line 92, valve 93 and line 51 to chamber 53 wherein any high-boiling components of the vapors, including any entrained tars or pitch-like material unsuitable for conversion with the reflux condensate from fractionator 54, are separated therefrom and commingle with the residual liquid withdrawn from chamber 53. In case the coking chamber is operated at a somewhat higher pressure than that employed in chamber 7 all or a portion of the vaporous products from the coking chamber may, when desired, be directed through line 94 and valve 95 into chamber 7 wherein undesirable high-boiling components of the vapors are collected together with the residual liquid withdrawn from this zone.

In case chamber 7 is operated at a substantial superatmospheric pressure it may be desirable to subject the residual liquid from this zone to further vaporization for the purpose of recovering desirable low-boiling components therefrom which are suitable for further conversion within the system to produce additional yields of motor fuel. For this purpose provision is made in the case here illustrated for supplying all or a regulated portion of the residual liquid withdrawn from chamber 7 by way of line 76 through line 96 and valve 97 into the reduced pressure vaporizing chamber 53 and this method of operation may be employed regardless of whether the process is operated for the production of liquid residue, coke, or both.

The preferred range of operating conditions which may be employed to accomplish the desired results in an apparatus such as illustrated and above described may be approximately as follows: The first mentioned or relatively heavy oil heating coil may employ an outlet conversion temperature ranging, for example, from 800 to 950° F. preferably with a superatmospheric pressure at this point in the system of from 100 to 500 pounds, or more, per square inch. Any desired pressure ranging from substantially atmospheric up to substantially the same pressure as that employed at the outlet from this heating coil may be utilized in the succeeding reaction or vaporizing chamber and this pressure may be substantially equalized or reduced in the succeeding fractionating, condensing and collecting portions of this stage of the system. The relatively light oil heating coil preferably employs an outlet conversion temperature ranging, for example, from 950 to 1050° F. and the pressure employed in this zone, as measured at the outlet therefrom, may range from a low superatmospheric pressure of 30 pounds, or thereabouts, per square inch to a superatmospheric pressure of 1000 pounds, or thereabouts, per square inch. The products from this coil are preferably cooled to a temperature of approximately 650 to 800° F., or thereabouts, prior to their introduction into the succeeding separating chamber which is preferably operated at a superatmospheric pressure of from 30 to 150 pounds, or thereabouts, per square inch, and this pressure may be substantially equalized or somewhat reduced in the succeeding fractionating, condensing and collecting portions of this stage of the system. The residue heating coil preceding the

coking chamber, when this stage of the process is employed, may utilize an outlet conversion temperature ranging, for example, from 900 to 1000° F. preferably with a superatmospheric pressure of from 30 to 300 pounds, or thereabouts, per square inch, and with a relatively short time element in this zone, as previously indicated. The coking chamber may be operated at any desired pressure ranging from substantially the same as that employed at the outlet from the communicating residue heating coil down to substantially atmospheric pressure.

As a specific example of one of the many operations of the process of the invention as it may be accomplished in an apparatus such as illustrated and above described, the charging stock comprises a Michigan crude of about 35.5° A. P. I. gravity containing approximately 28.5 per cent of 400° F. end-point straight-run gasoline having an octane number of approximately 43 by the motor method. The charging stock is supplied to the fractionator of the relatively mild cracking stage of the process from which is removed an overhead distillate product containing all of the straight-run gasoline and the motor fuel produced in the relatively mild cracking stage as well as somewhat higher boiling components of the charging stock and of the conversion products from the relatively mild cracking stage boiling up to approximately 500° F. The higher boiling components of the charging stock and the total intermediate liquid conversion products of the process, comprising the reflux condensate formed in the fractionator, are subjected in the heating coil of this stage to an outlet conversion temperature of approximately 920° F. at a superatmospheric pressure of about 400 pounds per square inch and this pressure is substantially equalized in the succeeding reaction chamber from which vaporous products are supplied to the same fractionator to which the charging stock is supplied while residual liquid products from the reaction chamber are supplied to the vaporizing and separating chamber of the relatively light oil cracking or reforming stage of the system. Said light distillate product recovered from the topping and relatively mild conversion stage is subjected in the light oil cracking or reforming coil to an outlet conversion temperature of approximately 980° F. at a superatmospheric pressure of approximately 890 pounds per square inch and the heated products from this zone are passed in indirect heat exchange with the distillate supplied thereto and are then introduced into the reduced pressure vaporizing and separating chamber which is operated at a superatmospheric pressure of approximately 50 pounds per square inch. This pressure is substantially equalized in the fractionating, condensing and collecting equipment of this stage of the system. Residual liquid from the reduced pressure vaporizing and separating chamber is quickly heated in a separate heating coil to an outlet conversion temperature of approximately 1000° F. at a superatmospheric pressure of about 60 pounds per square inch and is then introduced into alternately operated coking chambers maintained at substantially the same pressure, wherein their high-boiling components are reduced to coke and from which vaporous products are supplied to said reduced pressure vaporizing and separating chamber. Reflux condensate from the fractionator of the relatively light oil cracking or reforming stage is returned to the first mentioned cracking coil. This operation will produce, per barrel of charging stock, 75

approximately 66 per cent of 400° F. end-point 5
motor fuel having an octane number of approxi-
mately 70 by the motor method and about 55
pounds of low volatile petroleum coke of uniform
quality and good structural strength, the re-
mainder being chargeable, principally, to uncondensable
gas.

I claim as my invention:

1. In a process for the conversion of hydrocar-
bon oils wherein oils of relatively high-boiling
characteristics recovered from within the system
are subjected to conversion conditions of cracking
temperature and superatmospheric pressure, the
resulting vaporous and residual liquid conversion
products separated and the vaporous products
subjected to fractionation in commingled state
with hydrocarbon oil charging stock for the proc-
ess, the improvement which comprises recovering
from the fractionating step any desirable low-
boiling components of the commingled charging
stock and vaporous conversion products, separat-
ing the remaining components of the commingled
materials into relatively low-boiling and high-
boiling fractions, subjecting the latter to said
conversion, separately subjecting said relatively
low-boiling fractions to independently controlled
conversion conditions of cracking temperature
and superatmospheric pressure, cooling the re-
sulting heated products sufficiently to prevent any
substantial further conversion thereof, separat-
ing the resulting partially cooled materials into
vaporous and residual liquid components, sub-
jecting the vapor to fractionation whereby their
insufficiently converted components are condensed
as reflux condensate, subjecting fractionated va-
pors of the desired end-boiling point from the
last mentioned fractionating step to condensa-
tion, recovering the resulting distillate, and sub-
jecting reflux condensate recovered from the last
mentioned fractionating step to conversion in the
first mentioned cracking stage of the system,
separately heating residual liquid from the separ-
ating stage of the first-mentioned cracking op-
eration to a high conversion temperature under
non-coking conditions, introducing the resultant
heated products to a coking zone wherein their
high-boiling components are reduced to coke, and
returning vaporous products from the coking zone
to the separating stage of the second-mentioned
cracking operation.

2. A process such as claimed in claim 1 where-
in residual liquid from the separating stage of
the first mentioned cracking operation, prior to
the heating thereof to said high conversion tem-
perature, is commingled in the separating stage
of the second mentioned cracking operation with
the partially cooled conversion products under-
going separation therein.

3. A process such as claimed in claim 1 where-
in partial cooling of the heated products in the
second mentioned cracking stage of the system
is accomplished by passing the same in indirect
heat exchange with at least a portion of said
low-boiling fractions supplied to this stage of
the system for conversion.

4. A process for the conversion of hydrocarbon
oils which comprises subjecting oils of relatively
high-boiling characteristics recovered from within
the system to conversion conditions of cracking
temperature and superatmospheric pressure in a
heating coil, introducing the heated products
into an enlarged reaction chamber also main-
tained at a substantial superatmospheric pres-
sure wherein vaporous and residual liquid con-
version products are separated, subjecting va-

porous products from said enlarged chamber to
fractionation in commingled state with hydro-
carbon oil charging stock for the process, recover-
ing from the fractionating step any desirable
low-boiling components of the commingled charg-
ing stock and vaporous conversion products,
separating the remaining components of the
commingled materials into selected relatively
low-boiling and high-boiling fractions, supplying
the latter to the first mentioned heating coil for 10
conversion, subjecting selected low-boiling frac-
tions recovered from the fractionating step to in-
dependently controlled conversion conditions of
cracking temperature and superatmospheric pres-
sure in a separate heating coil, cooling the heated 15
products discharged from said separate heating
coil sufficiently to prevent any substantial fur-
ther conversion thereof, introducing the resulting
partially cooled products into a separating cham-
ber operated at substantially reduced pressure 20
relative to that employed in the last mentioned
heating coil wherein they are separated into
vapors and liquid residue, subjecting the vapors
from said separating chamber to fractionation
whereby their insufficiently converted compo- 25
nents are condensed as reflux condensate, sub-
jecting fractionated vapors of the desired end-
boiling point from the last mentioned fractionat-
ing step to condensation, recovering the result-
ing distillate, returning reflux condensate re- 30
covered from the last mentioned fractionating
step to conversion in the first mentioned heating
coil, withdrawing residual liquid from the reac-
tion chamber, introducing the same into said re-
duced pressure vaporizing chamber, withdrawing 35
non-vaporous liquid residue from the reduced
pressure vaporizing chamber, heating the same in
another separate heating coil to a high conversion
temperature under non-coking conditions, intro-
ducing the resulting heated products into a cok- 40
ing chamber wherein their high-boiling compo-
nents are reduced to coke, and returning vaporous
products from the coking chamber to one of the
aforementioned separating zones of the system
wherein vaporous and residual liquid products are 45
separated.

5. A process such as claimed in claim 4 where-
in said partial cooling of the heated products
from the second mentioned heating coil is ac-
complished, at least in part, by passing the same 50
in indirect heat exchange with at least a portion
of said relatively low-boiling fractions supplied
thereto.

6. A process such as claimed in claim 4 where-
in charging stock for the process, comprising a 55
hydrocarbon oil of relatively wide boiling range,
is supplied to said reaction chamber.

7. A process such as claimed in claim 4 where-
in hydrocarbon oil charging stock for the process
is supplied to the first mentioned fractionating 60
stage of the system.

8. In a process for the conversion of hydro-
carbon oils wherein oils of relatively high-boiling
characteristics recovered from within the system
are subjected to conversion conditions of cracking 65
temperature and superatmospheric pressure, the
resulting vaporous and residual liquid conversion
products separated and the vaporous products
subjected to fractionation in commingled state
with hydrocarbon oil charging stock for the proc-
ess, the improvement which comprises recovering
from the fractionating step any desirable low-
boiling components of the commingled charging
stock and vaporous conversion products, separat-
ing the remaining components of the commingled 75

5 materials into relatively low-boiling and high-boiling fractions, subjecting the latter to said conversion, separately subjecting said relatively low-boiling fractions to independently controlled conversion conditions of cracking temperature and superatmospheric pressure, cooling the resulting heating products sufficiently to prevent any substantial further conversion thereof, separating the resulting partially cooled materials 10 into vaporous and residual liquid components, subjecting the vapor to fractionation whereby their insufficiently converted components are condensed as reflux condensate, subjecting fractionated vapors of the desired end-boiling point 15 from the last mentioned fractionating step to condensation, recovering the resulting distillate, and subjecting reflux condensate recovered from the last mentioned fractionating step to conversion in the first mentioned cracking stage of 20 the system, separately heating residual liquid from the separating stage of the second-mentioned cracking operation to a high conversion temperature under non-coking conditions, introducing the resultant heated products to a coking 25 zone wherein their high-boiling components are reduced to coke, and returning vaporous products from the coking zone to the separating stage of the second-mentioned cracking operation.

9. The process as defined in claim 1 further 30 characterized in that additional vaporous products from the coking zone are returned to the first-mentioned cracking operation.

10. The process as defined in claim 8 further 35 characterized in that additional vaporous products from the coking zone are returned to the first-mentioned cracking operation.

11. A conversion process which comprises heating hydrocarbon oil to cracking temperature un-

der pressure in a heating coil, separating resultant vapors and unvaporized oil, fractionating the vapors in commingled state with charging oil for the process to form a relatively heavy cracking stock and a lighter cracking stock, supplying said heavy stock to said coil, subjecting said lighter stock to independently controlled cracking conditions of temperature and pressure in a second heating coil and then separating the same into vapors and residue, fractionating the former 10 and returning resultant reflux condensate to the first-named coil, heating at least a portion of said unvaporized oil to high conversion temperature in a third coil and distilling the same to coke in a coking zone, and supplying vaporous products 15 from the coking zone to the separating stage of the first-mentioned cracking operation.

12. A conversion process which comprises heating hydrocarbon oil to cracking temperature under pressure in a heating coil, separating resultant vapors and unvaporized oil, fractionating the vapors in commingled state with charging oil for the process to form a relatively heavy cracking stock and a lighter cracking stock, supplying said heavy stock to said coil, subjecting said lighter 20 stock to independently controlled cracking conditions of temperature and pressure in a second heating coil and then separating the same into vapors and residue, fractionating the former and returning resultant reflux condensate to the first-named coil, heating at least a portion of said unvaporized oil to high conversion temperature in a third coil and distilling the same to coke in a coking zone, and supplying vaporous products 25 from the coking zone to the separating stage of the second-mentioned cracking operation.

CHARLES H. ANGELL.
